to Kenlit Mfg. Co., Medford, Mass., a corpora-
tion of Massachusetts

Application September 17, 1948, Serial No. 148,639

Term of patent 3½ years

(Cl. D15—8)

To all whom it may concern:

Be it known that I, Richard Glassman, a citizen
of the United States, residing at San Francisco,
in the county of San Francisco, State of
California, have invented a new, original, and
ornamental Design for a Baby Sit-Up Cushion,
of which the following is a specification, refer-
ence being had to the accompanying drawing,
forming a part thereof.

In the drawing:

Figure 1 is a perspective view of a baby sit-up
cushion, showing my new design;

Figure 2 is a plan view of the said baby sit-up
cushion.

I claim:

The ornamental design for a baby sit-up cushion,
as shown.

RICHARD GLASSMAN.
